UNITED STATES PATENT OFFICE

2,278,251

TRANSMISSION SYSTEM

Robert B. Dome, Bridgeport, Conn., assignor to
 General Electric Company, a corporation of
 New York

Application May 5, 1941, Serial No. 391,902

3 Claims. (Cl. 178—44)

My invention relates to circuits for transmission of currents having frequencies extending over a wide range and it has for one of its objects to provide simple and effective means for effecting such transmission with uniform attenuation over said range.

A further object of my invention is to provide such circuits in which the adjustment necessary for uniform transmission of a desired band of frequencies is independent of coupling between coupled circuits, as between the different stages of an amplifier.

Another object of my invention is to provide such a circuit which is well adapted for operation between a source and a load having unequal impedances.

Still another object of my invention is to provide such a system in which all of the shunt capacitance of the system may be considered as a single capacity in shunt with the circuit for all of the purposes of computation, or adjustment, of the constants of the various elements of the system.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which Fig. 1 represents an embodiment of my invention and Fig. 2 represents a modification thereof.

Referring to Fig. 1 of the drawing I have illustrated my invention therein as employed in the circuits between a pair of electron discharge devices 1 and 2 where it may be employed to serve for the transmission of currents from one stage 1 of an amplifier to the second stage 2 thereof with uniform attenuation over a wide band of frequencies. Such an arrangement is especially adapted for use in connection with the amplification of the video currents in television systems, for example, or in other types of systems where it is necessary to transmit currents having frequency extending between a definite lower limit F_1 , which is above zero, and a higher limit F_2 . In television systems these frequencies F_1 and F_2 may be as much as four megacycles, or more, apart.

Signals to be amplified may be supplied between the grid and cathode of the amplifier 1 through a coupling condenser 3 from a source not shown. Operating potential is supplied to the

anode of the amplifier 1 from a source of unidirectional potential 4 through an inductance 5, the source being by-passed by the usual by-pass condenser 6. Signal potentials appearing on the anode of the discharge device 1 are supplied through a coupling condenser 7 to the grid of discharge device 2, the latter of which may be connected to the cathode through a high resistance 8 and a source of bias potential 9. The condenser 7 may be a large coupling capacitor such that its impedance is negligible over the band of frequencies to be transmitted. Similarly, the resistance 8 may be very high such that its shunt conductance may be neglected at frequencies to be transmitted.

In accordance with my invention an additional shunt path is provided comprising a resistance 10, an inductance 11 and a condenser 12, the inductance 11 being adjusted to resonate with the condenser 12 at the mean frequency of the band to be transmitted. The shunt capacitance of the circuit including the interelectrode capacitances of the discharge devices, and the shunt circuit capacitances may, for the purposes of my invention, be considered as a single capacitance connected in shunt with the circuit as indicated by the dotted lines 13. The inductance 5 may then be proportioned to resonate with the capacitance 13 at the mean frequency of the band to be transmitted, that is, at the same frequency at which the inductance 11 resonates with the condenser 12.

With the system thus adjusted the inductance 5 and condenser 13 resonate at the mean frequency and thus produce high impedance in shunt with the signal channel. Since inductance 11 and condenser 12 resonate at this same frequency the series impedance of these two elements is zero, the resistance 10 is effectively in shunt with the circuit and thus acts as a damping resistance upon the tuned circuit 5, 13.

In Fyler Patent No. 2,190,513 it has been shown that to obtain uniform transmission over a band of frequencies extending from zero to a very high frequency and involving damping of a resonant circuit that the damping resistance of the circuit should be approximately equal to the capacitive reactance of the circuit at the highest frequency to be amplified. That is in mathematical terms

$$R = \frac{1}{2\pi F_2 C}$$

It has been found in accordance with my invention that this relation applies to the circuit of Fig. 1 if the mean frequency of the band, i. e.,

the frequency at which elements 11 and 12 resonate, be considered to correspond to the lower frequency, zero, of the band of frequencies considered in the Fyler patent. That is,

$$R = \frac{1}{2\pi(F_2 - F_1)C} \quad (1)$$

where R is the resistance of the resistor 10 and C is the shunt capacitance of the system which is that indicated at 13. As the frequency departs from the mean frequency, the impedance of the circuits 5, 13, of course, reduces, whereas the series impedance of the elements 11 and 12 increases. These two effects tend to compensate each other to produce a uniform impedance over the band of frequencies to be transmitted, the increased series impedance of inductance 11 and capacitance 12 reducing the loading on the circuit 5, 13 produced by resistance 10.

To produce such uniform impedance over any desired band of frequencies, the reactance in series with the resistance 10 should be half of the resistance of the resistor 10 at the frequency F_2 , i. e. at the highest frequency in the band, or

$$2\pi F_2 L_1 - \frac{1}{2\pi F_2 C_1} = \frac{R}{2} \quad (2)$$

where L_1 is the inductance of the inductance 11 and C_1 is the capacitance of condenser 12. This is a value which has been mentioned in Fyler Patent No. 2,190,513 and may mathematically be demonstrated to be proper for the purposes of producing uniform impedance over the band. Similarly, the reactance in series with the resistance 10 at the lower frequency F_1 should be half of the resistance of the resistor 10, or

$$2\pi F_1 L_1 - \frac{1}{2\pi F_1 C_1} = -\frac{R}{2} \quad (3)$$

Then, solving Equations 2 and 3 simultaneously for C_1 , we obtain

$$C_1 = \frac{F_2 - F_1}{\pi R F_1 F_2} \quad (4)$$

Solving Equations 2 and 3 simultaneously for L_1 , we obtain

$$L_1 = \frac{R}{4\pi(F_2 - F_1)} \quad (5)$$

Now, solving Equations 4 and 5 for the resonant frequency F_0 , we obtain

$$F_0 = \sqrt{F_1 F_2} \quad (6)$$

The inductance L of the coil 5 must resonate with the capacity C, represented at 13 at the frequency F_0 cycles per second. Therefore,

$$L = \frac{1}{4\pi^2 F_0^2 C} = \frac{(F_2 - F_1)R}{2\pi F_1 F_2} \quad (7)$$

Since in setting up the system the capacitance 13 is generally known, as are also the frequencies F_2 and F_1 , the values of the different elements of the system may be calculated from these equations.

Fig. 2 represents a modification of my invention in which the shunt circuit 10, 11, 12 of Fig. 1 is dispensed with and in place thereof elements 14, 15 and 16 are added. The element 14 is an inductance resonating with the condenser 15 at the mean frequency of the band to be transmitted, these elements being connected in series with the coil 5. In shunt with the tuned circuit 14, 15 is the damping resistance 16. Inductance 5 is, of course, adjusted as before with respect to the condenser 13.

As thus arranged, it will be seen that at the

resonant frequency F_0 , that is, the mean frequency of the band, the impedance across the combination 14, 15 is that of the resistance 16 since the combination 14, 15 is resonant, and thus has extremely high, or infinite, impedance.

This resistance 16 acts as a damping, or loading, resistance on the circuit 5, 13, which is also resonant at this mean frequency F_0 . At frequencies departing from the mean frequency F_0 the elements 5 and 13 depart from resonance as do also the elements 14 and 15. Thus, the impedance across condenser 15, and hence in shunt with loading resistance 16, reduces the loading on the circuit 5, 13 thereby compensating for the reduced shunt impedance produced by the departure of the frequency from the resonance frequency of elements 5 and 13. Thus, the transmission property of the circuit between the two amplifiers is maintained substantially constant over the frequency band.

At the resonant frequency of the system the effective resistance of the circuit between the anode and cathode of discharge device 1 should be equal to R_0 where

$$R_0 = \frac{1}{2\pi(F_2 - F_1)C} \quad (8)$$

where C is the capacitance indicated at 13. Since resistance R of resistor 16 is in series with the inductance L of coil 5, then

$$R = \frac{L}{CR_0} = \frac{1}{4\pi^2 F_0^2 R_0 C} \quad (9)$$

Substituting in 8 and 9 for R_0 ,

$$R = \frac{F_2 - F_1}{2\pi F_1 F_2 C} \quad (10)$$

Since L must resonate with C at the frequency F_0 , ($\sqrt{F_1 F_2}$), it becomes

$$L = \frac{1}{4\pi^2 F_1 F_2 C} = \frac{R}{2\pi(F_2 - F_1)} \quad (11)$$

Then, by deduction

$$C_1 = \frac{1}{\pi(F_2 - F_1)R} \quad (12)$$

where C_1 is the capacity of condenser 15. Then also, by deduction

$$L_1 = \frac{R(F_2 - F_1)}{4\pi F_1 F_2} \quad (13)$$

where L_1 is the inductance of the coil 14. Now, solving Equation 10 for C, we have

$$C = \frac{F_2 - F_1}{2\pi F_1 F_2 R} \quad (14)$$

With the various elements of the system computed in accordance with these equations, the system will have uniform impedance and hence uniform attenuation over the entire band of frequencies extending from the frequency F_2 to the frequency F_1 , and the frequency F_1 may be any desired frequency above zero.

While I have shown particular embodiments of my invention, it will, of course, be understood that I do not wish to be limited thereto since different modifications may be made and I contemplate by the appended claims to cover any such modifications as fall within the true spirit and scope of my invention.

What I claim as new and desire to secure by Letters Patent of the United States is:

1. The combination, in a transmission circuit for currents having a wide range of frequencies, of inductance and capacity each connected in shunt to said circuit and resonant at a frequency

within said band, a shunt combination of resistance, inductance and capacity connected in series with one of said first mentioned elements and resonate at the same frequency, said resistance damping said first mentioned elements at said frequency.

2. The combination, in a coupling circuit for wide band amplifiers, of an inductance element and capacity element in shunt with said circuit and resonating at a frequency within said band, a resistance connected to damp said circuit at said resonant frequency, and a second inductance and capacity resonating at said frequency, and connected in shunt with said resistance and in series with one of said first mentioned elements to reduce said damping as the frequency departs from the frequency of said resonance.

3. The combination, in a signal channel for transmitting a wide band of frequencies, an in-

ductance element and capacity element connected in paths across said circuit and resonating at a frequency within said band, a resistance connected to damp the resonance of said inductance and capacity at said frequency and a second inductance and capacity resonant at said frequency connected in shunt with said resistance and in series with one of said first mentioned elements to reduce the damping of said resistance on said first inductance and capacity as the transmitted frequency departs from said first mentioned frequency, said resistance, inductance, and capacity and said inductance and capacity elements being proportioned with respect to each other to produce uniform transmission through said channel for all currents having frequencies within the band to be transmitted.

ROBERT B. DOME.
